UNITED STATES PATENT OFFICE.

ROY T. AXE, OF SYRACUSE, NEW YORK, ASSIGNOR TO THE O. M. EDWARDS COMPANY, INC., OF SYRACUSE, NEW YORK, A CORPORATION OF NEW YORK.

COMBINED SASH HOLDER AND STARTER.

Application filed April 14, 1927. Serial No. 183,881.

This invention relates to combined sash starters and holders of the type set forth in the application of Edward F. Chaffee, Sr. No. 165,513, filed February 3, 1927, and has for its object, a particularly simple and efficient arrangement of the sash starting member whereby, it is shifted laterally out of its normal position unless held in its normal position by reason of its frictional engagement by 10 the window frame or sill and whereby it is returned to its starting position during return movement of the sash holding mechanism.

The invention consists in the novel features 15 and in the combinations and constructions hereinafter set forth and claimed.

In describing this invention, reference is had to the accompanying drawings in which like characters designate corresponding parts 20 in all the views.

Figure 1 is a front elevation, partly broken away, of one form of this combined sash holder and starter, the contiguous part of the window frame being also shown.

25 Figure 2 is an inner face view of this combined sash holder and starter, the position the sash starter would assume when the sash is lifted off the sill and when the operating finger lever is actuated being shown in dotted 30 lines.

Figure 3 is a sectional view on line 3—3, Figure 1.

This combined sash starter and holder comprises generally, a base, sash holding mechanism carried by the base including a movable element, a sash starting member connected to said element to be moved thereby when said element is operated, and means for shifting the starting member laterally during the downward movement thereof including a spring tending to resist such lateral movement and to return the starting member to its original position.

The sash starter and holder also includes 45 means movable with the holding mechanism for positively shifting the starter member to its original position, as the sash holding mechanism returns to its starting position.

50 1 designates the base which may be of any suitable form, size and construction, it being here shown as a casing or a block formed with a recess 2 opening through its rear face or its face opposed to the sash 3, the base being secured to the sash in any suitable manner as by screws. The sash holding mecha-

nism is spring pressed, that is, it is pressed into holding position by a spring, and the mechanism here shown includes a movable holding element as a sliding bolt 4 and an operating element, the bolt being suitably guided in the base or casing 1 and having a tooth or teeth 5 projecting out of the recess 2 in position to coact with the rack or similar device 6 on the window frame 7.

The operating element is here shown as a lever 8 pivoted within the casing at 9 and having a short arm 10 and an angular radial arm 11 at an angle to the short arm 10, these two arms 10 and 11 being in the general form of a bell crank, the arm 11 coacting with the holding bolt 4 to operate it against its returning spring 13. This operating lever 8 also has a finger engaging portion arranged in juxtaposition to a grip or pinch handle 14 rigid with the casing 1. The arm 11 also serves to positively return the sash starting member to its original position during the returning movement of the holding mechanism to its holding position under the influence of the spring 13.

80 The sash holder mechanism forms no part of this invention and is of the general type shown in Chaffee Patent No. 1,567,571, December 29, 1925.

15 designates the sash starting member, 85 said member being movable vertically in the base 1 along the back wall of the recess 2 and moves crosswise of the direction of movement of the operating element and the bolt 4 on a plane parallel to the planes of movement of 90 these parts and the starting member is connected to one of these parts as the operating element.

95 Yielding or resilient means is provided for shifting the starting member laterally except when its lower end is not held from shifting movement, this yielding means also acting to return the member 15 to its original position as the sash holding mechanism returns to its normal original position or the 100 position in which the bolt 4 is interlocked with the rack 6. The starting member 15 is here shown as pivoted to the arm 10 at 16 of the operating element and normally extends vertically through a slot 17 in the lower side 105 of the base 1, the slot being of greater width than the member 15 in order to permit the lateral movement thereof about the pivot 16. As here illustrated, the member 15 and the base 1 are formed with spaced apart shoul- 110

ders and one of these shoulders is yielding and the shoulders are arranged to come into engagement after the vertical downward movement of the member 15 is started, in order to shift the member 15 laterally unless it is held from lateral movement by reason of its engagement with an abutment on the window frame as the abutment 19 on the sill 20.

In the illustrated embodiment of my invention, the member 15 is formed with a spring arm or shoulder 21 arranged to engage a fixed shoulder 22 as the boss to which the lever 8 is pivoted. The shoulder 21 is a flat spring. Thus, during downward movement of the member 15 when the lever 8 is actuated to withdraw the bolt 4, the shoulder 21 engages the shoulder 22 and becomes tensioned so that it tends to pull the member 15 laterally about its pivot 16 out of alignment with the abutment 19 unless such lateral shifting is prevented by reason of the engagement of the lower end of the member 15 with the abutment 19. When the force applied to the lever 8 is released, this spring reacts and returns the member 15 to vertical position although primarily this spring shifts the member 15 out of vertical position while the arm 11 positively returns the member 15 to vertical position. The parts are so arranged that the lever 15 extends vertically crosswise of the end of the arm 11 and is in the path of movement of the arm 11 when said member 15 is out of vertical position and hence, will be positively forced into normal position by the arm 11, the operator releases his hold on the finger lever 8.

In operation, when the sash is down, the operator by moving the handle 8 toward the pinch handle 14 withdraws the bolt 4 and likewise moves the member 15 downwardly and as it is in line with or against the abutment 19 or comes into engagement with the abutment 19 before the arm 21 engages the arm 22, a downward thrust is applied to this member 15 which prays the sash away from the sill. While the sash is being lifted, the member 15 swings laterally out of vertical position under the influence of the spring arm or shoulder 21. When the operator releases his hold on the handle 8, the parts return to their original position. The movement of this member 15 out of vertical position during the lifting of the sash is incidental only. During the lowering of the sash, the operator pinches the handle 8 toward the handle 14 in order to withdraw the bolt 4 from the rack 6. This movement also shifts the starting member 15 out of alignment with the abutment 19 so that the sash can be brought down onto the sill or completely closed while the member 15 passes to one side of the abutment 19. Hence, the sash can be fully closed without interference from the starting member 15. However, when the sash is completely closed, and the operator

releases the handle 8, the parts return to their original position under the influence of the springs 13 and 21, the starting member 15 moves upwardly and laterally from its inclined position over and into alignment with the abutment 19. It will be understood that usually there is a combined sash holder and starter on each of the lower corners of the sash.

What I claim is:

1. A sash starter and holder comprising a base, sash holding mechanism carried by the base including a movable element, a sash starting member movably connected to said element and movable laterally relatively thereto and also downwardly thereby to pry against the window frame when said element is operated to withdraw said mechanism and means for shifting the starting member laterally relatively to said element during the downward movement thereof including spring means acting on the starting member to return it to its original position and arranged to be tensioned by the downward movement of the starting member.

2. A sash starter and holder comprising a base, sash holding mechanism carried by the base including a pivoted element, a sash starting member pivoted to said element and movable downwardly thereby to pry against the window frame when said element is operated to withdraw the sash holding mechanism and yielding means for shifting the starting member laterally on its pivot during the downward movement thereof.

3. A sash starter and holder comprising a base, sash holding mechanism carried by the base including a movable element, a sash starting member movably connected to said element and movable laterally relatively thereto and also downwardly thereby to pry against the window frame when said element is operated to withdraw said mechanism and means for shifting the starting member laterally relatively to said element during the downward movement thereof including spring means acting on the starting member to return it to its original position, said shifting means including parts normally spaced apart and arranged to come into engagement during the downward movement of the starting member thereby forming a lost motion connection arranged to delay the lateral shifting.

4. A sash starter and holder comprising a base, sash holding mechanism carried by the base including a movable element, a sash starting member movably connected to said element and movable laterally relatively thereto and also downwardly thereby to pry against the window frame when said element is operated to withdraw said mechanism and means for shifting the starting member laterally relatively to said element during the downward movement thereof, said means in-

- cluding a spring shoulder and a fixed shoulder, one being carried by the base and the other by said starting member, one shoulder being arranged in the path of the other.
- 5 5. A sash starter and holder comprising a base, sash holding mechanism carried by the base including a movable element, a sash starting member pivotally connected to said element and movable downwardly thereby to 60
trolled by the movement of the operating element to move it to its normal position during the return movement of the operating element and the sash holding mechanism to holding position.
- 10 6. A sash starter and holder comprising a base, sash holding mechanism carried by the base including a movable element, a sash starting member pivotally connected to said element and movable downwardly thereby to 65
pry against the window frame when said element is operated to withdraw said mechanism and means for shifting the starting member laterally on its pivot during the downward movement thereof, said means including a spring shoulder and a fixed shoulder normally spaced apart, one being carried by the base and the other by said starting member, one shoulder being arranged in the path of the other.
- 15 7. A sash starter and holder comprising a base, sash holding mechanism carried by the base including a movable element, a sash starting member pivotally connected to said element and movable downwardly thereby to 70
pry against the window frame when said element is operated to withdraw the holding mechanism, said element also having an arm and the sash starter member extending transversely of the end of said arm, means for shifting the starter member laterally on its 75
pivot during the downward movement thereof and said arm being arranged to move away from the starting member during the lateral movement thereof and to move into engagement therewith during the return movement of the operating element and to positively shift the starting member on its pivot to its original position.
- 20 8. A sash starter and holder comprising a base, sash holding mechanism carried by the base including a movable element, a sash starting member pivotally connected to said element and movable downwardly thereby to 80
pry against the window frame when said element is operated to withdraw said mechanism and means for shifting the starting member laterally on its pivot during the downward movement thereof, said means comprising a laterally extending spring shoulder carried by the starting member and a fixed shoulder carried by the base, the fixed shoulder being arranged in the path of the spring shoulder.
- 25 9. A sash starter and holder comprising a base, sash holding mechanism carried by the base including a movable element, a sash starting member pivotally connected to said element and movable downwardly thereby to 85
pry against the window frame when said element is operated to withdraw said mechanism and means for shifting the starting member laterally on its pivot during the downward movement thereof, said shifting member being movable crosswise of said element in a plane parallel to the plane of movement of said element.
- 30 10. A sash starter and holder comprising a base, sash holding mechanism carried by the base including a movable element, and a sash starter member connected to said element to be operated thereby, said member being movable crosswise of said element in a plane parallel to the plane of movement of 90
said element.
- 35 11. A sash starter and holder comprising a base having a recess therein, sash holding mechanism carried by the base including a movable element, a sash starting member movably connected to said element, said mechanism and the sash starting member being located in the recess and the sash starting member extending crosswise of said mechanism and in a plane parallel to the 95
plane of movement of said elements.
- 40 12. A sash starter and holder comprising a base having a recess therein, sash holding mechanism carried by the base including a movable element, a sash starting member movably connected to said element, said mechanism and the sash starting member being located in the recess and the sash starting member extending crosswise of said mechanism adjacent the back wall of the recess in a plane parallel to the plane of movement of 100
said element.
- 45 13. A sash starter and holder comprising a base having a recess therein, sash holding mechanism carried by the base including a movable element, a sash starting member movably connected to said element, said mechanism and the sash starting member being located in the recess and the sash starting member extending crosswise of said mechanism adjacent the back wall of the recess in a plane parallel to the plane of movement of 105
said element.
- 50 14. A sash starter and holder comprising a base, sash holding mechanism carried by the base and including a movable element, a sash starter member connected to said element and movable downwardly thereby to 110
pry against an abutment on the window frame when said element is operated to withdraw the holding mechanism, means for shifting the starting member laterally during the downward movement thereof and means con-
- 55

In testimony whereof, I have hereunto signed my name, at Syracuse, in the County of Onondaga, and in the State of New York, 115 this 13th day of April, 1927.

ROY T. AXE.
